UNITED STATES PATENT OFFICE.

ADOLPH L. DE LEEUW, OF HAMILTON, OHIO, ASSIGNOR TO THE NILES TOOL WORKS COMPANY, OF HAMILTON, OHIO.

TOOL-RELIEF FOR METAL-PLANERS.

SPECIFICATION forming part of Letters Patent No. 713,614, dated November 18, 1902.

Application filed February 13, 1902. Serial No. 93,820. (No model.)

To all whom it may concern:

Be it known that I, ADOLPH L. DE LEEUW, a citizen of the United States, residing in Hamilton, Butler county, Ohio, (post-office address 5 Hamilton, Ohio,) have invented certain new and useful Improvements in Tool-Reliefs for Metal-Planers, of which the following is a specification.

This invention, pertaining to improvements 10 in tool-reliefs for metal-planers, will be readily understood from the following description, taken in connection with the accompanying drawings, in which—

Figure 1 is a side elevation of portions of 15 an ordinary metal-planing machine provided with a tool-relief exemplifying my present invention; Fig. 2, a diagram illustrating electric circuits controlling the magnetic relieving device; Fig. 3, a front elevation of the tool- 20 box and its immediate attachments; Fig. 4, a vertical section of the same; and Fig. 5 a plan of the same, one of the magnet-spoils appearing in horizontal section.

In the drawings, 1 indicates the bed of an ordinary metal-planer, 2 the table, 3 the housings, 4 the rail, 5 the saddle, 6 the swivel, 7 the slide, 8 the tool-box, 9 the tool-clamps, 10 the apron, all the parts thus far referred to being of ordinary construction; 11, a pair 30 of electromagnet-spoils mounted on the front face of the upper portion of the tool-box above the hinge of the apron, the axes of the spoils being parallel and projecting forwardly from the tool-box in a common horizontal plane parallel with the axis of the hinge-pivot of the apron; 12, an armature disposed across in front of the cores of the electromagnet and standing normally some little distance forward of the magnet-poles;

35 40 45 50

13, a lever-arm projecting rigidly upward from the apron to the rear of the armature and between the magnet-spoils; 14, a pair of studs projecting rigidly forward from the face of the tool-box above the magnet-spoils; 15, hangers projecting up from the armature and having their upper ends pivoted in the forward ends of studs 14, whereby the armature is pivotally suspended; 16, a set-screw through the central portion of the armature, its inner end being adapted to impinge against the forward face of lever-arm 13; 17, a switch-lever

mounted on the planer-bed; 18, a pin carried by a dog adjustable along the planer-bed and adapted to strike and shift the switch-lever as the table nears the completion of its entering stroke; 19, a similar dog-pin adapted to shift the switch-lever as the table nears the completion of its return stroke; 20, a segmental contact-piece adapted to be engaged by the switch-lever; 21, a second contact-piece 60 adapted to be engaged by the switch-lever while it is in engagement with contact-piece 20, but of lesser lengthwise extent, so that the switch-lever may continue to engage with contact-piece 20 after passing off of contact-piece 21; 22, a contact-piece in prolongation of but separate and insulated from contact-piece 21, contact-piece 20 having such extent of length that it may be engaged by the switch-lever when the latter is in engagement with either of the contact-pieces 21 or 22; 23, an electric circuit leading from a source of electric energy, one of its members passing through the coils of the electromagnet 11 and terminating at contact-piece 20, while its other 75 member goes to and terminates at contact-piece 21; 24, an electrical resistance device typified by an electric lamp in a branch of that member of the circuit terminating at contact-piece 21; 25, the circuit branch just 80 referred to, the same going through resistance 24 and terminating at contact-piece 22, and 26 that member of the circuit terminating at contact-piece 21.

Referring to Figs. 3, 4, and 5, when the 85 apron 10 is home in the tool-box in cutting position the armature 12 stands away from the magnet-poles, being suspended by the hangers 15 and the end of set-screw 16 being in or nearly in contact with the face of lever-arm 13. If the electromagnet be sufficiently energized, then the armature will be drawn toward it, resulting in the pushing rearward of lever-arm 13 and the swinging forward of the lower portion of the apron and the consequent elevation and relief of the tool. This action on the part of the electromagnet is to take place when the tool is to be lifted, the apron falling again and restoring the tool to cutting position when the magnet is de-energized. The cores of the spoils are shown as threaded directly into the metal of the

tool-box, which latter therefore forms the heel-bar of the magnet. The suspension device of the armature should be of non-magnetic metal, and the pole-faces of the magnet 5 or armature should also be armed with non-magnetic metal.

The switching of the current to and from the electromagnet is effected by the dogs, adjustable along the planer-table, which dogs 10 may be the ones usually provided upon planers, the intention being that the magnet is inert while the table is making its cutting stroke, the current going to and energizing the magnet and lifting the tool just before 15 the reversal of the table motion takes place, the tool being held in elevated position of relief while the table is making its backing stroke and dropping again to cutting position by the deenergization of the magnet just before 20 the table reverses at the beginning of the cutting stroke.

The armature normally stands at some distance from the pole-faces of the magnet, and the work of initiating the tipping of the apron 25 and tool is comparatively heavy, thus requiring such a strength of current as might damage the spools if maintained throughout the backing stroke of the planer. The attractive power of the magnet becomes greater 30 as the armature approaches it, and when the armature shall have completed its active motion then the air-gap is practically *nil* and comparatively little current may sustain the apron and tool in tilted position. I therefore 35 arrange for a preliminary application of heavy current to the electromagnet to do the work of lifting the tool, this being followed by a reduction of the current strength to a point sufficient to maintain the tool in lifted 40 position without danger to the electromagnet. This may be understood from Figs. 1 and 2, in which the switch-lever is in idle position, corresponding with the cutting stroke of the planer. It will be observed in Fig. 2 that 45 the circuit is entirely open and that consequently the electromagnet 11 is inert. As the table nears the completion of its cutting stroke after the finish of the cut, but before reversal, dog-pin 18 shifts the switch-lever 50 to contact-pieces 20 and 21, thus putting the full current through the electromagnet 11, under which conditions the magnet becomes powerfully energized, and the apron and tool 55 become tilted to position of relief. The table continues its backward motion, and the switch-lever travels off of contact-pieces 21 and onto contact-piece 22, thus leaving the circuit closed only through the resistance 24, the current thus reduced being sufficient to 60 maintain the tool in relief position. Under these conditions the table makes its reversal and completes its backing stroke, the switch-lever remaining on contact-pieces 20 and 22. As the table nears the end of its backing 65 stroke then dog-pin 19 shifts the switch-lever first off of contact-piece 22 onto contact-piece 21 and finally out of all contact, under which

condition the circuit is opened, the magnet deenergized, the tool allowed to fall to cutting position, and the table makes its reversal and performs its cutting stroke, and so on and on. It will be apprehended that when the table completes its backing stroke and the switch-lever is being thrown from light-duty position on contact-piece 22 to idle position 70 of open circuit it passes over high-duty contact-piece 21, thus putting again to the electromagnet the full strength of the current. This incidental momentary application of the full current strength, while of no benefit, 80 does no harm.

I claim as my invention—

1. In a tool-relief for metal-planers, the combination, substantially as set forth, of a tool-carrying part mounted for motion in a direction to effect the relief of the tool away from the surface being planed, an electromagnet, an armature having connection with said tool-carrying part, an electric circuit connected with said electromagnet, a branch from 90 said circuit through an artificial resistance, a switch adapted to open said circuit and to close it either through said electromagnet direct or through said electromagnet and artificial resistance, and adjustable dogs arranged to move in unison with the planer-table and serving to actuate said switch.

2. In a tool-relief for metal-planers, the combination, substantially as set forth, of a tool-box, an apron hinged therein, a lever-arm 100 projecting from the apron, an electromagnet mounted on the tool-box, an armature coöperating with said electromagnet and engaging said lever-arm, an electric circuit for energizing the electromagnet, a switch for controlling said circuit, and dogs arranged to move in unison with the planer-table and serving to actuate said switch.

3. In a tool-relief for metal-planers, the combination, substantially as set forth, of a tool-box, an apron hinged therein, a lever-arm projecting from the apron, an electromagnet mounted on the tool-box, a pivotally-supported armature coöperating with said electromagnet and engaging said lever-arm, an electric circuit for energizing the electromagnet, 115 a switch for controlling said circuit, and dogs arranged to move in unison with the planer-table and serving to actuate said switch.

4. In a tool-relief for metal-planers, the combination, substantially as set forth, of a tool-box, an apron hinged therein, a lever-arm projecting upwardly from the apron, a pair of magnet-spoils projecting from the face of the tool-box and straddling said lever-arm, an armature disposed in front of said magnet-spoils and engaging said lever-arm, an electric circuit for energizing said spools, a switch for the control of said circuit, and dogs to actuate the switch.
